UNITED STATES PATENT OFFICE.

JAMES R. KEISER, OF BROOKLYN, NEW YORK.

DESIGN FOR A SCARF.

SPECIFICATION forming part of Design No. 15,994, dated March 24, 1885.

Application filed December 27, 1884. Term of patent 3½ years.

To all whom it may concern:

Be it known that I, JAMES R. KEISER, of Brooklyn, in Kings county, and the State of New York, have invented or produced a new and original Design for Scarfs, of which the following is a specification.

My design relates to scarfs of the kind which represent tied knots.

I will describe a scarf embodying my design, and then point out the design in a claim.

The accompanying drawing is a front view of a scarf embodying my design.

A A' designate two aprons or portions representing the ends of a bow.

15 B designates the portion representing the cross portion of a bow. It inclines downwardly from one side of the scarf to the other.

C designates the band of the scarf. Above the portion B extends a portion, D. This is

in the form of a puff. It protrudes farther 20 above the portion B of the scarf at the center than at the sides of the scarf, and it is of curved profile. It has also several flutes or folds, a. It materially enhances the appearance of the scarf.

25 What I claim as my design, and desire to secure by Letters Patent, is—

The design for a scarf, consisting of the aprons or portions A A', the cross-piece B, and a puffed portion above the cross-piece B, 30 of curved profile, extending from side to side of the cross-piece, having flutes or folds, substantially as shown and described.

JAMES R. KEISER.
